CLAIM

The ornamental design for a footwear outsole as shown and described.

DESCRIPTION

FIG. 1 is a side perspective view of a footwear outsole showing my new design.

FIG. 2 is a bottom plan view thereof;

FIG. 3 is a top plan view thereof;

FIG. 4 is a side elevational view thereof;

FIG. 5 is an opposite side elevational view thereof;

FIG. 6 is a front elevational view thereof; and,

FIG. 7 is a rear elevational view thereof.

The even dashed broken lines represent portions of the footwear that form no part of the claimed design.

1 Claim, 5 Drawing Sheets
